ATTORNEY

UNITED STATES PATENT OFFICE

HARRY L. FINK, OF NEW YORK, N. Y.

TERRAZZO STRIP

Application filed December 7, 1929, Serial No. 412,320. Renewed May 5, 1932.

The invention consists in a new and improved dividing or pattern-forming strip such as is used in various plastic surfacing structures, and especially in terrazzo floors, where 5 a variegated design is to be exposed on the finished surface. For convenience, therefore, the new strip will be referred to hereinafter as a terrazzo strip, and the advantages of the same will be described in connection with the 10 laying of terrazzo floors.

A terrazzo strip, as is well known in the art, is laid during the laying of the floor, and forms an inbuilt part of the completed floor.

One of the objects of the present invention 15 is to provide a terrazzo strip, which may be cheaply formed, as by a stamping operation, for instance out of thin sheet brass; and which, while having portions displaced from the general plane of the strip, for interlocking 20 with the plastic material on one or both sides of the strip, will present these displaced portions otherwise than as tabs or tongues.

Another object is to provide a terrazzo strip 25 of great strength and rigidity and small cost, and at the same time one incorporating portions displaced from the general plane of the strip, for performing the interlocking function aforesaid.

Another object is to provide a terrazzo strip 30 wherein the displaced portions are nonuniplanar projections, preferably formed by stretching as well as displacing the strip material.

To these ends I form in the strip integral 35 projecting straps or loops and cross-bonding apertures corresponding generally to the strap or loop outlines and locations, said strap formations being preferably inclined downward and outward in relation to the plane of the strip, and the projections being located alternately at opposite sides of the strip.

The characteristics and advantages of the invention are further sufficiently explained in 45 connection with the following detail description of the accompanying drawing, which shows a representative embodiment. After considering this example, skilled persons will understand that many variations may be made within the limits defined by the appended claims.

This application is a continuation in part, of my prior applications, Serial No. 196,230, filed June 3, 1927 and Serial Number 269, 340, filed April 12, 1928.

Fig. 1 is a perspective view of a terrazzo 55 strip, embodying the invention in one form.

Fig. 2 is a cross section of the strip, in position in a terrazzo floor.

The strip 6, of suitable sheet metal, usually brass or bronze, and of moderate thickness, has a plurality of spaced integral strap-like projections, or bonding loops, 14, formed by cutting or punching and pressing and stretching the strip material. The projections or loops are preferably alternately on 60 opposite sides of the strip, and may be located at desired positions width-wise of the strip. Preferably in some cases as shown, the loop formations may be located relatively near the lower edge of the strip. The upper and lower edges 15, 16 of the straps or loops may be parallel, as shown, but this is not essential. Preferably, in the formation of the loops they are inclined to the plane of the strip, this inclination being outward and 65 downward, as best shown in Fig. 2, providing a wedging action on the material of the screed, or base layer 20 of the floor structure. 70

In the formation of the loops or straps, 75 slots or openings 17 are produced in the strip, and the material of the screed will flow or be forced through these openings, forming cross bonds through the strip between the base material at opposite sides 80 thereof, to retain the strip in very firm interlocking engagement with the base layer after the latter sets. The angular arrangement or downward flaring angle of the straps 85 exerts a wedging action on the base material as the strip is pushed down therein, insuring the proper flow of the material about the loop portions and through the slots to form 90 the cross bonds. 95

The strip is usually so located in the screed that the upper edges of the strap portions are flush with the upper surface of the screed or base layer. Thereafter the upper or terrazzo layer 21 is filled in flush with the upper edges of the terrazzo strips, as usual.

I claim:

1. A dividing strip having therein spaced integral loop-form bonding projections inclined downwardly outward in relation to the plane of the strip.
2. A dividing strip having therein spaced integral loop-form bonding projections inclined downwardly outward in relation to the plane of the strip, the projections being located alternately at opposite sides of the strip.
- 10 3. A dividing strip having therein strap projections consisting of integral portions of the strip stretched to approximate arc form, and cross-bonding slots corresponding substantially to the strap portions, the strap portions being inclined outwardly downward in relation to the plane of the strip.
- 20 4. A dividing strip having therein spaced, integral loop-form projections and cross bonding apertures substantially corresponding to the outline and location of the projections, the projections being inclined downwardly outward in relation to the plane of the strip.
- 25 5. A laterally flexible dividing strip having a substantially straight upper edge and having substantially flat side walls, and a plurality of spaced loop-form bonding projections struck out from the material of said strip.
- 30 6. A laterally flexible dividing strip having a substantially straight upper edge and having substantially flat side walls, and a plurality of loop-form bonding projections struck out from the material of said strip and positioned alternately at opposite sides of the strip.

In testimony whereof I affix my signature.
HARRY L. FINK.

DISCLAIMER

1,888,031.—*Harry L. Fink*, New York, N. Y. TERRAZZO STRIP. Patent dated November 15, 1932. Disclaimer filed October 27, 1933, by the patentee.

“5. A laterally flexible dividing strip having a substantially straight upper edge and having substantially flat side walls, and a plurality of spaced loop-form bonding projections struck out from the material of said strip.”

Hereby disclaims the subject-matter of said claim which is in the above stated words except when the construction covered by such claim is embodied in a strip having a body portion of a single thickness of material and a zone adjacent its upper edge of a single thickness of material, the strip being pushed as a unit into, and being supported by, plastic material which hardens about the same, and being of the type sometimes referred to as a terrazzo strip.

[*Official Gazette November 21, 1933.*]

1. A dividing strip having therein spaced integral loop-form bonding projections inclined downwardly outward in relation to the plane of the strip.
2. A dividing strip having therein spaced integral loop-form bonding projections inclined downwardly outward in relation to the plane of the strip, the projections being located alternately at opposite sides of the strip.
- 10 3. A dividing strip having therein strap projections consisting of integral portions of the strip stretched to approximate arc form, and cross-bonding slots corresponding substantially to the strap portions, the strap portions being inclined outwardly downward in relation to the plane of the strip.
- 20 4. A dividing strip having therein spaced, integral loop-form projections and cross bonding apertures substantially corresponding to the outline and location of the projections, the projections being inclined downwardly outward in relation to the plane of the strip.
- 25 5. A laterally flexible dividing strip having a substantially straight upper edge and having substantially flat side walls, and a plurality of spaced loop-form bonding projections struck out from the material of said strip.
- 30 6. A laterally flexible dividing strip having a substantially straight upper edge and having substantially flat side walls, and a plurality of loop-form bonding projections struck out from the material of said strip and positioned alternately at opposite sides of the strip.

In testimony whereof I affix my signature.
HARRY L. FINK.
